UNITED STATES PATENT OFFICE.

FRANK H. BACHELDER, OF ORANGE, MASSACHUSETTS.

DISPENSING CABINET.

Application filed May 2, 1924. Serial No. 710,586.

This invention relates to improvements in dispensing cabinets and more particularly to a cabinet adapted for use in the sale and the dispensing of needles and shuttles.

I have previously invented and obtained a patent dated February 22nd, 1921, numbered 1,369,213 upon a needle and shuttle selling cabinet which incorporates to some extent the ideas embodied in the present invention. The present invention however is designed as an improvement over the patent mentioned and these improvements consist of certain details of construction which will be hereinafter more specifically described.

The primary object of my invention is to provide a cabinet adapted to contain packages of needles of different sizes and for different machines and also shuttles for different machines and to so construct the cabinet that a salesman can quickly and accurately obtain the needle or shuttle desired by the purchaser.

Another object of my invention is to provide containers of novel construction for the needles and shuttles whereby the particular articles desired can be quickly located and removed from the cabinet and delivered to the purchaser.

Another object of my invention is to provide a cabinet having a revolvable shaft which supports a plurality of radiating needle package carrying pockets and a plurality of shuttle compartments combined with improvements for rotating the shaft and stopping a particular pocket at the dispensing point of the cabinet where the articles can be removed from the pockets for delivery to the purchaser.

A still further object of my invention is to provide a needle containing pocket which is pivotally mounted so as to enable the pocket to be swung outwardly through the dispensing opening of the cabinet to enable a rapid and easy removal of needles for delivery to the purchaser.

Other further objects, novel features of construction and approved results of my invention will be particularly pointed out in the following description and accompanying drawings.

In the drawings:

Figure 1 is a perspective view of a needle and shuttle cabinet embodying my invention.

Figure 2 is a vertical transverse sectional view through Figure 1.

Figure 3 is a top plan view of a cabinet

with the top removed showing the spiral arrangement of the notched plate.

Figure 4 is an enlarged fragmentary perspective view of a portion of the under side 60 of the top showing the manner of supporting the sliding pointer and the manner of steadyng the pointer in its set position.

Figure 5 is an enlarged detailed perspective view of the pivotally mounted needle 65 pocket disclosing the manner in which the pocket is attached to its supports, the pocket being shown in position for dispensing.

Figure 6 is an enlarged detailed perspective view of a shuttle pocket showing the manner in which it is supported.

Figure 7 is an enlarged sectional view of the sliding pointer.

My dispensing device consists of a suitable case which, in the form here shown, comprises a rectangular bottom housing 1 and a circular drum or housing 2 supported thereupon in the manner shown in the drawings.

Extending vertically through both the lower and upper drums 1 and 2 is a shaft 3 the lower end of which is retained in a suitable bearing 4 in the bottom 5 of the lower housing while its upper end terminates in a suitable bearing or hub carried in the top ring 6.

The bottom drum or housing 1 is provided with a top 7. Supported upon the shaft 3 by means of a suitable key 8 or the like 90 which extends through the shaft and its vertical walls 9 there is a horizontal plate 10 to the bottom of which is suitably bolted or fastened a second horizontal plate 11. At spaced intervals along the outer peripheral 95 edge of the plate 11 are notches 12 behind which are cut out portions 13 bent downwardly, as more clearly appears in Fig. 6.

The shuttle pockets are designated at 14 and are adapted to receive the cardboard 100 containers 15 in which the shuttles are dispensed to the merchants to be placed in the cabinet. The shuttle pockets 14 of the cabinet are supported in the shallow rectangular elongated supports 16 provided 105 with an open outer end. The side walls of the supports adjacent their open ends are flared outwardly as at 17 to facilitate the easy removal of the pockets while the outer ends of the bottom of the supports are bent 110 slightly upward as at 18 to retain the pockets in the support. In removing the pockets it

is necessary to lift them slightly so that they will disengage the upwardly bent portion 18 and they can then be slid or lifted outward.

The supports 16 for the shuttle pockets are fastened to the plate 11 in a novel manner which consists of providing a downwardly struck portion 19 in the bottom of the supports midway their length and providing an extending tongue 20 at the inner 10 end of the bottom of the supports. The downwardly struck portion 19, as clearly appears in Figure 2 of the drawings slides into the notched portion 12 of the plate 11 and abuts the bottom of this plate while 15 the tongue 20 is inserted downwardly through the opening 13 of the plate 11 and bent upwardly against the bottom of the plate, all of which clearly appears in Figure 2 of the drawings. In this manner the supports 20 are securely fastened to the plate. The supports are in spaced relation upon the plate and extend radially outwardly therefrom entirely around the peripheral edge of the plate, the outer ends of the pockets 25 being supported adjacent the vertical wall of the housing 1. It will clearly appear that the rotation of the shaft 3 will rotate the plate 11 and consequently rotate the shuttle pockets.

30 Supported upon the top 7 of the lower housing is a ring 21 the outer face 22 of which is preferably nickel plated to add to the appearance of the cabinet. This outer face 22 extends upwardly to form a vertical wall 35 behind which is a groove adapted to receive the curled end 23 of the circular drum vertical wall 24. The ring 21 is held in place upon the top 7 by means of suitable bolts 25 the nuts 26 of which are adapted 40 to engage and clamp downwardly the wire ring 27 which firmly clamps the ends 23 of the housing wall 24 in place. The upper end of the housing wall 24 is likewise provided with a curled end 28 adapted to seat 45 within the groove provided in the top ring 6. The outer edge 29 of the top ring extends downwardly and is preferably nickel plated to add to the appearance of the cabinet. Extending through the ring portion 50 6 are suitable bolts 30 the nuts 31 of which are adapted to engage and clamp the circular wire ring 32 to hold the upper ends of the housing wall 24 in place in the ring.

The needle dispensing pockets are designed at 32 and are hollow rectangular members adapted to receive suitable cardboard containers 33 in which the needles are dispensed to the merchants to be placed in the cabinet. The needle pocket supports are designated at 34 and are rectangular in shape having open tops, bottoms and fronts. The needle pockets are pivotally supported upon the supports at 35 so that they will telescope into the supports as shown in Figure 2 or can be swung outwardly to the ex-

tended position shown in Figure 5. The supports 34 are mounted upon the circular horizontal plates 36 and 37 in a novel manner. These two plates are provided at their peripheral edges with outwardly extending 70 tongues 38 while the supports 34 are provided with openings 39 and 40 in their rear walls. The upper end of the rear wall of the supports is additionally provided with the inwardly extending horizontal tongues 75 or flanges 41. It will be seen that the flanges 41 of the supports are adapted to rest upon the upper circular plate 36 while the tongues of this plate extend through the openings 39 of the support and are bent backwardly 80 and downwardly upon the flange 41. The tongues 38 of the lower plate 37 are adapted to extend outwardly through the openings 40 of the supports and be bent upwardly on the inside of the supports as clearly appears at 42 in Figure 2 of the drawings. In this manner the needle pockets and needle 85 pocket supports are securely fastened and supported by the two horizontal plates without the use of bolts or screws. 90

The plates 36 and 37 are supported upon and fastened to the shaft 3 by means of a flange casting which comprises a top 43 and a bottom 44 with upwardly extending walls 45 surrounding the shaft. The plates 36 and 37 are suitably fastened to the top and bottom respectively of the flange casting by means of rivets 46 or the like while the vertical walls 45 of the casting are securely fastened to the shaft by means of a key 47 or its equivalent. It will be seen that any rotation of the shaft 3 will rotate the needle pockets and their supports. 95 10

Extending transversely the upper circular drum below the needle pockets is a horizontal shaft 48 the inner end of which is supported in a suitable bearing 49 and carries a gear 50 which engages a gear 51 carried by the shaft 3. The outer end of the shaft 48 is provided with a knurled wheel 52. Through the medium of this wheel the shaft 3 can be rotated which in turn rotates both the needle pockets and the shuttle pockets. 10 11

Fastened to the top 43 of the flange coupling in the upper housing 2 by means of suitable screws 53 is a circular plate 54 which carries a plurality of upwardly extending stops or notches 55 which are spirally arranged, as clearly appears in Figure 3 of the drawings. The purpose of these stops will be hereinafter described. 11 12

The housing 2 has its upper end suitably closed by a top 56 the peripheral edges of which sit in a suitable depression formed in the top of the ring 6. The top 56 is provided with a longitudinal slot 57 over which a pointer is adapted to slide. The pointer comprises a head 58 carrying at opposite sides pointers 59 while the head is further provided with a downwardly ex- 11

tending stem 60, the stem 60 being suitably fastened in a block which slides between the two horizontal bars 62 and 63 which form an integral part of the top ring 6. The 5 vertical edges of the sliding block are provided with grooves adapted to receive the inwardly extending edges of the two plates 64 and 65 carried upon the bottom of the horizontal rods and be supported thereby. 10 Suitably fastened upon the bottom of the sliding block 61 is a downwardly extending spring detent 66 which is adapted to engage the stops or notches 55 of the plate 54. The sliding block 51 is further provided 15 with a horizontally extending spring detent 67 which is adapted to engage the shallow depressions 68 in the inner side of the horizontal rod 62. These depressions represent the plurality of points at which the 20 pointer will be set and will steady the pointer in these set positions.

On one side of the slot 57 there is designated the letters of the alphabet from A to O and above this the heading "Needles". 25 At the other edge of the slot there is the same list of letters under the heading "Shuttles". The depressions 68 which engage the horizontal detent 67 are placed in a line with these letters. 30 At the front of the upper housing 2 in a line with the slot 57 is an opening 68' of a size and shape to allow the needle pockets to be swung outwardly through the same. This opening is preferably surrounded by 35 and finished off with a nickel plated edge 69 to add to the appearance of the cabinet. In the front of the lower housing 1 and in a line with the opening in the upper housing is an opening 70 of a size and shape to 40 permit the shuttle pockets to be lifted outwardly therethrough. As appears in Figures 1 and 6 the shuttle pockets are provided with suitable handles 71 to adapt their being lifted outwardly. The opening 45 70 is preferably provided with a nickel plated edging 72 to add to the appearance of the cabinet. This edging has an extending portion 73 which extends over and rests upon the top 7 of the housing and carries an upwardly extending rubber post 74. 50 This post will support and form a stop for the needle pockets when they are swung outwardly through the openings in the upper drum.

55 Printed in suitable lists upon the top 56 are the names of all of the sewing machines manufactured and in use in this country. Opposite the name of the machine is a letter which designates the kind of needle and shuttle used in this machine.

60 It will now be seen that if a purchaser desires a needle or a shuttle for the "Remington" machine the merchant places the pointer opposite the letter O and rotates the shaft 3 through the medium of the knob 52

until the spring detent 66 engages the proper stop. When this occurs the proper needle and proper shuttle boxes are opposite the openings 68 and 70 respectively. In this manner the merchant has quickly 70 and easily located the article which the purchaser desires and all that remains for him to do is to swing the needle pocket outwardly and procure the package of needles or to slide the shuttle pocket out and procure 75 the desired shuttle.

I desire it to be readily understood that the merchants purchase the shuttle and needles in pasteboard boxes and to replenish the cabinet the merchant merely removes the 80 empty cardboard container from the needle or shuttle pocket and replaces it with a loaded container.

Having thus described my invention what I desire to protect and claim by Letters 85 Patent is:

1. A dispensing cabinet comprising a housing, a rotatable member in the housing, supports connected to the said rotatable member, the said supports having open tops and outer ends, a vertically arranged pocket with an open inner side, said pocket telescoping the said support, the housing having a vertical opening through which the said pocket may be moved outward through said openings to permit access to its contents. 95

2. A dispensing cabinet comprising a housing, a rotatable member in the housing, vertically arranged supports connected with the rotatable member by means of interlocking projections and openings, said supports having open outer sides and tops, a vertically arranged pocket movable within the said support, the support having an open inner side, the housing having a vertical opening elongated beyond the end of the pocket whereby said pocket may be moved outward through the opening to permit access to its contents. 100 105

3. A dispensing apparatus comprising a housing, a rotatable member within the housing, the housing having a vertical opening, pocket supports having open outer sides attached to the rotatable member, a pocket pivoted at its outer lower corner to the outer 110 lower corners of the said support, whereby the said pocket can be swung wholly outside of the housing through the opening therein. 115

4. A dispensing cabinet comprising a housing, a rotatable member in the said housing, the housing having an opening, pocket supports having open fronts and tops attached to the rotatable member, pockets with open inner sides pivoted at their outer lower corners to the outer lower corners of the supports, said pockets adapted to swing outward through the opening in the housing to permit access to the contents of the pockets. 120 125

5. In a dispensing cabinet of the type de- 130

scribed, a rotating plate having outwardly extending tongues at its peripheral edge, and a pocket supporting member having openings in its rear wall, the plate tongues 5 extending through said openings and bent to clamp said pocket supporting member, and a pocket pivotally mounted in said supporting member.

6. In a dispensing cabinet of the type described, a supporting plate having outwardly 10 extending tongues at its peripheral edge, a pocket supporting member composed of a continuous piece of material bent into a U-shape, the back of the U forming the back of 15 the member and extending above and below the side walls thereof and provided with openings, the plate tongues extending through said openings and bent backwardly to clamp the plate for supporting the pocket 20 supporting member.

7. In a dispensing cabinet of the type described, a supporting plate having outwardly

extending tongues at its peripheral edge, a U-shaped pocket supporting member having extensions provided with openings, the 25 plate tongues extending through said openings and the tongues and the extensions of the supporting member beyond the openings bent backwardly to clamp the plate, and a pocket pivotally mounted in said supporting 30 member.

8. In a dispensing cabinet of the type described, a supporting plate having outwardly 35 extending tongues, a telescopic arranged pocket and supporting member, said supporting member being provided with openings and the plate tongues extending through said openings and bent to clamp the plate, whereby the supporting member is securely fastened to and supported by the plate. 40

In testimony whereof I hereunto affix my signature.

FRANK H. BACHELDER.
